ABSTRACT OF THE DISCLOSURE

This invention relates to an improved process for the production of alkyl- or cycloalkyl tin halides by the direct reaction of metallic tin with alkyl- or cycloalkyl halides, comprising carrying out the reaction in the presence of an organo-antimony compound, or a mixture consisting of organo-antimony compounds as a catalyst.

The present invention relates to a process for the production of alkyl- or cycloalkyl tin halides, respectively, by the direct reaction of metallic tin with alkyl- and cycloalkyl halides, respectively, or mixtures of alkyl- and/or cycloalkyl halides.

In the technical production of alkyl tin halides, the direct reaction of metallic tin with alkyl halides offers considerable advantages over the methods already known in which tin tetrachloride is used as the starting material, which is converted either with a Grignard compound or with an alkyl aluminum compound into the tetra-alkyl tin compound, from which the desired alkyl tin halide is produced in a second reaction step by means of a disproportionation reaction with tin tetra halide.

A number of processes for the direct reaction of metallic tin with alkyl halides in which use is made of highly reactive alkyl halides, especially iodides, is already known. However, in most cases these iodides are too expensive for the technical production of alkyl tin halides; therefore, there is a need for a process by which the cheaper alkyl bromides and especially alkyl chlorides can be directly converted with high yields to the corresponding alkyl tin halides. According to a process which is also known, this can be achieved by using arsenic or antimony halides as a catalyst for the reaction, but the process concerned mainly aims at the conversion of higher alkyl halide homologues, i.e. alkyl halides in which the alkyl group contains more than four carbon atoms. In another known process, for the production of alkyl tin halides, the reaction may be carried out in the presence of an alcohol, an ether, an ester or tetrahydrofuran and in the presence of certain metals and/or alkyl metal halides. The necessity of using specific solvents, however, is a serious drawback of this known process.

An improved process has now been found for the production of alkyl tin halides by direct reaction of metallic tin with alkyl halides, by means of which process both alkyl bromides and alkyl chlorides with lower alkyl groups, such as the ethyl-, propyl- and butyl compounds, and alkyl bromides and alkyl chlorides with higher alkyl groups, such as the hexyl-, heptyl- and octyl compounds, as well as cycloalkyl halides, such as the cyclohexyl com-

2

pounds, can be converted to mixtures of the corresponding alkyl- and cycloalkyl tin halides, respectively, with good yields, and without the necessity of using specific solvents.

According to this invention the process for the production of alkyl or cycloalkyl tin halides by the direct reaction of metallic tin with alkyl- or cycloalkyl halides, respectively, or mixtures of alkyl and/or cycloalkyl halides at higher temperatures, is characterised by the fact, that 5 the reaction is carried out in the presence of a catalytic amount of an organo-antimony compound or a mixture consisting of organo-antimony compounds.

In general, when this process is used, the dialkyl- and dicycloalkyl tin dihalides, respectively, are obtained as the main product of the reaction, whereas the monoalkyl- and monocycloalkyl tin trihalides, respectively, are formed as by-products, as well as, most often in smaller quantities, the trialkyl- and tricycloalkyl tin monohalides, respectively.

By the term "organo-antimony compound" is meant a compound of trivalent or pentavalent antimony, in which at least one alkyl-, alkenyl-, cycloalkyl-, aryl-, alkaryl- or aralkyl group is directly bonded to an antimony atom. If there are two or more of the said groups in the compound, these groups may differ. Compounds of a more complex structure, such as tetraorgano diantimony compounds or complexes of tetraorgano antimony with metal halides or with halogens, are also included in the above definition.

The following are examples of organo-antimony compounds, which may be used as catalysts according to this invention: triethyl antimony, tri-n-butyl antimony, tri-isobutyl antimony, di-n-butyl antimony bromide, di-n-butyl antimony chloride, monobutyl antimony dibromide, ethyl dibutyl antimony, tetrabutyl antimony bromide, tri-butyl antimony dibromide, diethyl tributyl antimony, tri-n-octyl antimony, di-n-octyl antimony bromide, divinyl antimony bromide, tricyclohexyl antimony, triphenyl antimony, diphenyl antimony chloride, phenyl antimony dibromide, tetraphenyl antimony bromide, tolyl antimony dibromide, tribenzyl antimony, tetraphenyl diantimony, bis(tetrabutyl antimony).mercuric iodide-complex

$\{(\text{H}_9\text{C}_4)_4\text{Sb}\}2 \cdot \text{HgI}_4$

bis(tetraphenyl antimony).germanium iodide bromide-complex $\{(\text{C}_6\text{H}_5)_4\text{Sb}\}_2 \cdot \text{GeI}_2\text{Br}_2$, tetraphenyl antimony iodide.iodine-complex $\{(\text{C}_6\text{H}_5)_4\text{SbI}\}\text{I}_2$, etc.

In the process according to this invention, the organo-antimony compounds are mostly added in amounts varying from 1 to 8 mol. percent, calculated on the tin used, 50 preferably in amounts from 3 to 5 mol. percent. In general, it is advisable to use, as a catalyst, an organo-antimony compound in which the organic group(s) is (are) the same as the alkyl- or cycloalkyl group, respectively, in the halide to be converted.

Furthermore, it was found that it may be of advantage, 55 in order to improve the conversion of the less reactive alkyl- and cycloalkyl halides, respectively, i.e. the bromides and chlorides, to add to these a small amount of elementary iodine or of an inorganic or organic iodide, e.g. an amount of 0.5 to 10 mol. percent, preferably of 1 to 3 mol. percent, calculated on the bromide or chloride present. In this way, to give an example, it is advantageous to add an alkyl- or cycloalkyl iodide, respectively, in which the organic group is the same as that in the alkyl- or cycloalkyl bromide or alkyl- or cycloalkyl

chloride used. The iodide can also be added in the form of an alkyl- or cycloalkyl tin iodide, respectively, e.g. as dialkyl tin diiodide or tin tetraiodide.

The process according to this invention may be carried out using the amounts of alkyl- or cycloalkyl halide, respectively, and tin in proportions which can be varied within wide limits. In this way, it is possible to use molecular ratios of e.g. alkyl- or cycloalkyl halides, respectively, to tin of 2:1 to 3:1, but also smaller or larger molecular ratios may be used.

The form and quality of the tin used as the starting material are not determinative for the carrying out of the process. In most cases, it is possible to achieve a very good reaction when using tin in the form of fine shavings but it is also possible to use fine or coarser powdered tin as the starting material.

In general, the reaction is carried out at temperatures between 130° and 210° C.; the reaction temperature is preferably chosen between 160° and 180° C. The process can be carried out both in a closed system under pressure and in an open system under atmospheric pressure, in which case the evaporating liquid is recycled by means of a reflux condenser. However, in the latter case, it is advisable, in particular for the conversion of the lower alkyl halides, to add inert solvents with a high boiling point so as to increase the reaction temperature.

In addition, in order to achieve as high a yield as possible, it is important, in those cases in which a catalyst sensitive to air is used, that the reaction be carried out in an inert atmosphere, e.g. under nitrogen.

The reaction mixture obtained can be further processed and the alkyl- or cycloalkyl tin halides, respectively, can be purified according to known processes, e.g. by means of distillation. For an analytical determination of the composition of the mixture good use can be made of the gas chromatographic method.

Any alkyl- or cycloalkyl halide, respectively, used in excess can practically entirely be recovered by distillation and used for a subsequent reaction, just as any solvents added. It was also found, that the antimony-containing residue from the distillation can often be advantageously used as a catalyst for a subsequent reaction.

The alkyl- or cycloalkyl tin halides, respectively, obtained according to the process of the present invention, in particular the dialkyl- or dicycloalkyl tin dihalides, constitute valuable intermediates for the preparation of alkyl- or cycloalkyl tin compounds, respectively, which are applied as plastics additives. The monoalkyl- or monocycloalkyl tin trihalides, respectively, and the trialkyl- or tricycloalkyl tin monohalides, respectively, which are formed as by-products of the process, also are valuable intermediates as such, but it is also possible to convert these compounds into the dialkyl- or dicycloalkyl tin dihalides, respectively by means of a disproportionation reaction, possibly by adding an amount of tetra-alkyl tin, or tetracycloalkyl tin, respectively.

The invention is further illustrated by means of the following examples.

EXAMPLE 1

6.0 g. pure tin in the form of fine shavings (0.1 to 0.3 mm. thick) and 21.0 g. n-butyl bromide are introduced into a Carius tube. After the air has been displaced by nitrogen 0.5 g. di-n-butyl antimony bromide is added and the tube is next heated under autogenous pressure at 180° C. for 16 hours, during which the tin completely goes into solution.

The contents of the tube are filtered off after cooling and the excess of butyl bromide is distilled off under reduced pressure. Part of the residue is methylated quantitatively and the mixture of methylbutyl tin compounds thus obtained is analysed chromatographically.

The analysis results show that of the tin added 63.0% has been converted into di-n-butyl tin dibromide and 24.8% into n-butyl tin tribromide and that no determinable amount of tri-n-butyl tin bromide is formed.

EXAMPLE 2

In the same way as described in Example 1, a test is made in which 6.0 g. tin and 21.0 g. n-butyl bromide are heated without any further addition being made. Even after 16 hours, no tin has been converted. This clearly shows the catalytic action of the organo-antimony compound.

EXAMPLE 3

10 A mixture of: G.
5 Tin ----- 6.0
n-Butyl bromide ----- 21.0
n-Butyl iodide ----- 2.0
15 and
Tri-n-butyl antimony ----- 0.5

is heated under autogenous pressure for 16 hours at 180° C. in a Carius tube, in which the air has been displaced by nitrogen. After the experiment has been completed, the reaction mixture is further processed in the same way as described in Example 1.

20 The analysis results show that of the tin added 70.6% has been converted into di-n-butyl tin dibromide and 14.3% into n-butyl tin tribromide and that no determinable amount of tri-n-butyl tin bromide is formed. In comparison with Example 1, this result shows the favourable effect of the addition of the alkyl iodide on the conversion into the dialkyl tin dihalide.

EXAMPLE 4

30 With a mixture of the following composition: G.
5 Tin ----- 6.0
n-Butyl chloride ----- 14.1
n-Butyl iodide ----- 2.0
35 and
Tri-n-butyl antimony ----- 0.5

40 separate tests are carried out in a Carius tube for 16 hours at temperature of 140°, 160°, 180° and 200° C., respectively. The following table summarizes the yields of butyl tin chlorides, calculated from the analysis results of the reaction mixtures obtained, based upon added tin:

45	Degrees centigrade.....	140	160	180	200
n-Butyl tin trichloride, percent.....	(¹)	11.5	12.5	7.5	
Di-n-butyl tin dichloride, percent.....	(¹)	55.8	72.7	24.4	
Tri-n-butyl tin chloride, percent.....	(¹)	9.5			
Total butyl tin chlorides, percent.....	20	76.8	85.2	31.9	

50 ¹ Not separately determined.

55 From these results it appears that the reaction has an optimum effect in the temperature range of 160° to 180° C.

EXAMPLE 5

A mixture of the same composition as indicated in Example 4, in which the tri-n-butyl antimony is replaced by triphenyl antimony, after being heated at 180° C. for 16 hours gives the following yields based upon added tin: di-n-butyl tin dichloride 53.8%, n-butyl tin trichloride 19.6% and tri-n-butyl tin chloride nil.

EXAMPLE 6

65 A mixture of: G.
5 Tin ----- 6.0
n-Butyl chloride ----- 14.1
Potassium iodide ----- 1.8
70 and
Tri-n-butyl antimony ----- 0.6

75 is heated for 16 hours at 180° in a Carius tube in which the air has been displaced by nitrogen. On completion of the experiment, 90% of the tin added has been converted a yield of 65.4% of di-n-butyl tin dichloride and a yield

of 6.2% of n-butyl tin trichloride, based upon converted tin, being obtained.

EXAMPLE 7

A mixture of:	G.	5
Tin -----	6.0	
n-Octyl bromide -----	24.9	
n-Octyl iodide ----- and	2.0	
Tri-n-butyl antimony -----	0.5	

is heated in a Carius tube for 16 hours at 180° C. in the same way as described above. A total yield of 80.2% of n-octyl tin bromides, based upon added tin, is obtained.

EXAMPLE 8

In the same way as described in the previous examples, a mixture of:

Tin -----	G.	6.0
Cyclohexyl bromide ----- and	24.5	
Tri-butyl antimony -----	0.5	

is heated in a Carius tube for 16 hours at 180° C. On completion of the experiment, it appears that 45% of the tin added has been converted into a mixture of cyclohexyl tin bromides.

A test, carried out with an identical mixture, to which 1.38 g. I₂ has been added, shows a conversion of 48.3% of the tin added.

EXAMPLE 9

A mixture of:	G.	
Tin (shavings of 0.1-0.3 mm.) -----	6.0	
n-Octyl bromide ----- and	58.0	
Bis (tetra-n-butyl antimony) · mercuric iodide-complex -----	2.0	

is introduced into a flask with reflux condenser and heated for five hours at 180° C. whilst stirring vigorously and whilst nitrogen is passed over the mixture. After filtration, the mixture obtained is processed in the same way as described in Example 1. It appears from the results that 87% of the tin added has been converted, a yield of 57.4% of di-n-octyl tin dibromide and a yield of 28.9% of n-octyl tin tribromide, based upon added tin, being obtained, while no determinable amount of tri-n-octyl tin bromide is formed.

EXAMPLE 10

In an autoclave, which is provided with a stirring mechanism, a mixture of:

Tin (powder of 0.1-0.3 mm. grain size) -----	G.	100.0
n-Butyl chloride -----	235.0	
n-Butyliodide ----- and	33.0	
Tri-n-butyl antimony -----	9.5	

is introduced after the air in the autoclave has been replaced by nitrogen. The autoclave is next heated at 175° C. for three hours, whilst the stirrer is rotated at a velocity of 480 rotations/min. During the reaction the pressure rises to approx. 9 kg./cm.².

After cooling, the contents of the autoclave is processed

as described in the foregoing examples. The results of this experiment show that 85.7% of the tin added is converted, whereby a yield of 71.5% di-n-butyl tin dichloride, 12.8% n-butyl tin trichloride and 9.0% tri-n-butyl tin chloride is obtained.

I claim:

1. In the process for the production of alkyl or cycloalkyl tin halides which comprises reacting metallic tin with an organic halide selected from the group consisting of alkyl halides and cycloalkyl halides at elevated temperatures in the presence of a catalyst for the reaction, the improvement which consists in conducting said reaction in the presence of from 1 mol percent to 8 mol percent, based on the amount of tin, of an organo-antimony compound selected from the group consisting of (a) trivalent and pentavalent antimony compounds having at least one organic group selected from the group consisting of alkyl, alkenyl, cycloalkyl, phenyl, tolyl, and benzyl bonded directly to the antimony and the remaining bonds of said trivalent and pentavalent antimony being bonded directly to a group selected from the group consisting of the aforesaid organic groups and halogen, (b) diantimony compounds having four organic groups selected from the group consisting of alkyl, alkenyl, cycloalkyl, phenyl, tolyl and benzyl bonded directly to the two antimonials, and (c) complexes of antimony compounds having four organic groups selected from the group consisting of alkyl, alkenyl, cycloalkyl, phenyl, tolyl and benzyl bonded directly to the antimony, with metal halides and halogens, as said catalyst for the reaction.

2. The process of claim 1 wherein said organo-antimony compound catalyst is present in an amount of from 3 mol percent to 5 mol percent.

3. The process of claim 1 wherein said organo-antimony compound catalyst contains only alkyl or cycloalkyl groups corresponding to said organic halides selected from the group consisting of alkyl halides and cycloalkyl halides.

4. The process of claim 1 wherein said elevated temperature is between 160° C. and 180° C.

5. The process of claim 1 wherein part of said organo-antimony compound catalyst is the antimony-containing distillation residues from a previous reaction.

6. The process of claim 1 wherein said organic halides are selected from the group consisting of chlorides and bromides.

7. A process for the production of n-butyl tin chlorides which consists essentially of reacting metallic tin with n-butyl chloride in a molecular ratio of 1:2 to 1:3 in the presence of from 3 mol percent to 5 mol percent, based on the amount of tin, of tri-n-butyl antimony and in the presence of from 0.5 mol percent to 10 mol percent, calculated on the amount of n-butyl chloride, of n-butyl iodide, at a temperature of between 160° C. and 180° C. and recovering said n-butyl tin chlorides.
